(57) **CLAIM**

The ornamental design for a finger ulnar deviation splint as shown and described.

DESCRIPTION

FIG. 1 is a front, left and top perspective view of a finger ulnar deviation splint, showing my new design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is another front, left and top perspective view of the finger ulnar deviation splint of FIG. 1 shown in an environment of use; and,

FIG. 10 is another rear, right and bottom perspective view of the finger ulnar deviation splint shown in another environment which combined with an unclaimed element.

The dashed broken lines shown in FIGS. 9 and 10 depict environmental structures that form no part of the claimed design.
